UNITED STATES PATENT OFFICE.

ISAAC B. KLEINERT, OF NEW YORK, N. Y.

ARMPIT-SHIELD.

SPECIFICATION forming part of Letters Patent No. 351,269, dated October 19, 1886.

Application filed July 13, 1886. Serial No. 207,874. (Model.)

To all whom it may concern:

Be it known that I, ISAAC B. KLEINERT, a citizen of the United States, residing at New York, in the county of New York and State of New York, have invented certain new and useful Improvements in Armpit-Shields, of which the following is a specification, reference being had therein to the accompanying drawings, in which—

10 Figure 1 represents a perspective view of my improvement. Fig. 2 is a vertical section of the rubber lining, showing the manner of joining the pieces thereof.

This invention relates to that class of armpit-shields in which there is no seam at the fold; and the object thereof is to obtain a dress-shield which shall be absolutely free from all uncertainty as to imperviousness.

The seamless shields heretofore made are all 20 more or less liable to be pervious, inasmuch as the coating usually applied to the surface of the material of which they are formed is a very thin compound, of which generally not more than one-half is rubber, the remainder 25 being of material that is insoluble or that does not thoroughly assimilate with the rubber, and the material thus coated is hence very liable to be found pervious at many points when the article comes to be worn, and subjected to the 30 action of the perspiration of the wearer. In addition to this objection, I have found that to produce a shield that can be considered in any wise as impervious, the coating must be made so thick as to be very bulky and cumbersome, 35 and hence it is objectionable on this score also.

In that class of shields formed of two pieces of rubber-coated material united at the fold, or elsewhere, there is, necessarily, an overlapping seam, which makes the article thicker at 40 this point by one thickness of the material and the layer of cement by which the two pieces are united, so that this part not only becomes very thick and clumsy, but is also comparatively stiff and harsh. Besides this, 45 the joint, although it may appear perfect to the eye, is frequently imperfectly made, and when subjected to the test of wear the perspiration may find its way through the imperfect place and ruin a costly dress before the trouble 50 is discovered.

To overcome these difficulties is the object of my present improvement; and the invention

consists in combining with an outer seamless covering an inner section of rubber tissue made in such a manner as to be seamless at 55 the joint, said coating being prepared with a filling to prevent its shrinking under the effects of perspiration and the inner section being made of as pure rubber as can be cured, without the coloring and other matters usually 60 added to give body to the same.

In carrying out my invention I preferably proceed in the following manner: I make the inner or rubber section, A, by stretching it into form or in any manner known to those 65 skilled in the art, but preferably by cutting out two crescent-shaped pieces, and then, by butting the concave pieces together, form a joint without any appreciable seam or additional thickness. This can readily be done 70 with the pure gum, owing to its cohesive quality, but not so easily when mixed with the other materials commonly incorporated in rubber compounds. With the pure gum a perfect joint can readily be made, and a lining section 75 is thus produced that is not only absolutely impervious, but one that will retain its proper curve at the fold under all reasonable circumstances. I now cover this lining with a seamless section, B, of some soft flexible material, 80 preferably of stockinet, which is first stretched or formed into a suitable shape, and then "saddled" over the rubber section and the edges trimmed to correspond, after which they may be united at the outer edges, either by binding 85 or plain stitching all around said edges or only a short distance down each side, leaving the lower part of the edges unattached to each other, whereby the advantage of ventilation is obtained, as the opening at the bottom admits 90 of a better circulation of air between the two sections when set to dry. Besides this advantage, the loose outer layer or covering is more easily "basted" to the dress, as the gum renders such basting difficult when both are 95 united all along the edges. If the parts are stitched together, the edges may or may not be "pinked," to give the same an ornamental appearance.

I have so far described the outer covering 100 as being made of plain stockinet; but I prefer to use a stockinet that has been prepared with a filling, either before or after it has been stretched or formed to the required shape.

This filling may be of some soft gum or water-proof size, provided with a suitable pigment to give a white color, so that the pores of the stockinet will be filled and the color of the 5 gum, which is naturally brown, will not show through the meshes. This hiding of the color is an important item, but the greatest advantage, and the main object of the filling, is to prevent the change of the shape of the covering material by the abundant moisture due to the perspiration of the wearer. The gum or size I prefer to use is composed of one-half rubber and the other half of oxide of zinc, whiting, or other substance which will mix 10 well with the rubber, and the whole may be mixed with any suitable or convenient solvent. I do not, however, confine myself to this compound, as others may be used with good effect; but a compound formed partly of 15 rubber I find preferable. By the construction of these two sections—that is to say, an inner section of pure rubber and a covering of filled stockinet—a very perfect shield is formed, for the rubber section is thoroughly impermeable, 20 the covering soaks up the perspiration, and the shield, as a whole and in its separate parts, retains its shape perfectly, while at the same time the shield is readily made, is quite handsome in appearance, is durable, and can be 25 readily dried when desired.

I wish it to be understood that I do not intend to use enough of the filling on the covering to make it water-proof, but only to put on sufficient of the filling to give it a body that 30 will prevent its shrinking with the perspiration and hinder the brown color of the gum from showing through the meshes. The better to allow of the absorption of the perspiration I apply the filling on the inner side only.

It will be found that the stockinet covering 35 on a pure rubber lining has a great advantage over the shield formed of pure rubber alone, for in case the latter is used without any covering the perspiration will not pass through it, but as it is entirely devoid of any absorbing 40 property the perspiration forms into drops and rolls down on the dress below the shield, and there does its destructive work in places where it will show more than if the perspiration 45 passed through the shield. For this reason alone, if for no other, the stockinet covering, either plain or filled, will be found to be 50

a great improvement on a pure rubber shield without such covering. The filled covering, however, will be found to be far the best, because it has been found that the acids used in curing the pure rubber shields have a very destructive effect on the textile goods used for the outside or covering; hence, if a filled covering is not used it is necessary that care should 55 be taken not to keep them long in stock, as otherwise there would be in the course of a year great loss from the destructive effect of the acids on the textile coverings. By the use of the filled coverings this effect will be avoided, 60 because the filling, which may be of some material—such as a compound of rubber—has an affinity for the acids used in curing, and therefore absorbs the vapor passing from the 65 cured rubber before it can reach the textile covering, and thus all danger of the destructive effect upon the textile covering is avoided. Moreover, if the covering has not been vulcanized, the acids passing from the inner section of the filling will tend to cure said filling, 70 and thus, instead of being destructive to the covering, the vapors of the acid produce a 75 useful effect.

What I claim as new is—

1. The combination, in an armpit-shield, of 80 a lining-section of rubber having a curved fold, and an outer seamless section of stockinet having a filling to hide the rubber and to prevent the shrinking of the stockinet, substantially as described.

2. The combination, in an armpit-shield, of 85 an inner section of rubber and an outer section of textile fabric having an absorbing filling to protect the covering from the effects of the acid in the rubber, substantially as described.

3. The combination, in an armpit-shield, of 90 a lining of rubber with a seamless covering of filled stockinet, the two being attached at the sides and loose at their other parts, substantially as described.

In testimony whereof I affix my signature, in presence of two witnesses, this 12th day of July, 1886.

ISAAC B. KLEINERT.
